UNITED STATES PATENT OFFICE.

HAROLD OLSSON, OF BATH, ENGLAND.

APPLIANCE FOR USE IN IMPARTING INSTRUCTION IN OR PRACTICING SWIMMING.

Application filed April 29, 1924. Serial No. 709,858.

To all whom it may concern:

Be it known that I, HAROLD OLSSON, a subject of the King of Great Britain, and a resident of Bath, in the county of Somerset, England, have invented an Improved Appliance for Use in Imparting Instruction in or Practicing Swimming, of which the following is a specification.

This invention relates to appliances for use in imparting instruction in or practicing swimming.

In accordance with the invention the improved appliance comprises a buoyant structure adapted to afford direct support to the chin of the pupil of swimmer. This structure which may also support other parts of the body and comprises one or more floats is preferably constructed in such manner that either the buoyancy thereof can be varied to enable the degree of support afforded to a pupil to be progressively decreased as the latter progresses in the art or the position of the chin support and/or other parts of the structure can be varied relatively to the centre of buoyancy of the structure so as to vary the point relative to the surface of the water at which the chin or other part of the body of the pupil or swimmer is supported.

For use in imparting instruction in or practicing either the breast or the overarm stroke, such for example as the stroke known as the "American crawl", the structure may comprise a main float to which are adjustably attached two diverging arms to the outer ends of which is connected a belt adapted to be attached to the body of the swimmer and carrying two auxiliary floats. The main float may carry a chin supporting means adjustably attached thereto and the auxiliary floats may be adjustable with respect to the main float in any suitable manner, as for instance by varying the effective length and/or inclination of the connecting arms. In some cases the main float may be provided with one or more downwardly projecting fins or keels or other means as for example an adjustable weight slidably attached to a vertical depending arm for ensuring lateral stability.

For use in imparting instruction in or practicing the breast stroke only, the structure may comprise a main float connected with two auxiliary floats by a pair of diverging arms. The main float is adapted for the reception of the chin of the swim-

mer or pupil and the auxiliary floats may be adjustable with respect to the main float as set forth above. Alternatively, the auxiliary floats may be replaced by a transverse 60 pad, or the like, preferably of buoyant material which connects the free ends of the divergent arms and is adapted to rest on or be attached to the pupil's back. In a modified form the main float may have the 65 chin supporting means adjustably attached thereto, which means may carry the arms by which the main float is connected with the other floats.

The structure may also, in a further modified form, comprise a number of similar floats connected by arms or the like carrying a supporting means for the chin. This supporting means may be attached to or rest on said arms substantially midway between the floats and in some cases may be adjustable in relation to the latter.

For imparting instruction in or practicing particularly what is commonly known as the "American crawl" or arm-over-arm stroke the structure may comprise a single float provided with one or more downwardly projecting fins or keels or other means as for example an adjustable weight slidably attached to a vertical depending arm, for 85 ensuring lateral stability with or without one or more arms or projections carrying a transverse pad as above described.

Supplementary to the buoyant structure proper two other floats may be provided 90 and adapted for attachment to the legs of the swimmer in such manner that when he is in the water they will afford the necessary support to his legs but will not hold them too near the surface.

In any form of the invention a coaming or breakwater is preferably provided which extends in front of the face of the pupil or swimmer and prevents the water from gaining access to his mouth and nose so as to give him greater confidence in his early efforts. And further, a vertical partition may extend across the whole or a portion of the interior of the main float, an aperture or apertures being provided in said partition so that when it is desired to decrease the buoyancy of the float and the latter is partially filled with water the partition controls the passage of water from one side of the float to the other, thereby assisting in preventing excessive rolling of the float.

In order that the invention may be more

clearly understood and readily carried into practice, reference will now be made to the accompanying drawings wherein several constructional forms thereof are illustrated 5 by way of example and in which Fig. 1 is a perspective view of one form of the buoyant structure proper, Fig. 2 a plan view of the main float, and Fig. 3 a perspective view showing a main float provided with a depending arm and adjustable weight. Fig. 10 Fig. 4 is a perspective view of another form of the invention and Fig. 5 is a similar view of one of the additional floats which may be provided for supporting the legs of the 15 pupil or swimmer. Figs. 6 and 7 are diagrammatic views showing two further modified forms.

The construction illustrated in Figs. 1 and 20 2 comprises a main float 1 on which are mounted a pair of diverging arms 2 which are adapted to be attached to a belt 3 fitted with two auxiliary floats 4. The floats 1 and 4 may consist of closed metallic or other receptacles normally full of air but provided 25 with necks or equivalent by which they may be partially filled with water or other liquid in order to vary their buoyancy or may be of material of suitable low specific gravity such as cork as hereinafter described with 30 reference to Fig. 4.

The float 1 is provided on its upper surface with a chin supporting member 5 adjustably secured thereto by means of a bolt 6 and wing nut 7 which bolt is fixed in the 35 float 1 and passes through holes 8 or a slot in the member 5 so that the latter may be moved relative to the centre of buoyancy of the structure. The chin supporting member may be provided on its upper surface with 40 inclined ribs or projections 9 and mounted in grooves 10 intermediate the forward ends of the ribs 9 is a screen or partition 12 adapted to be raised or lowered as required so as to control access of water to the mouth and 45 nose of the pupil. As well as the screen 12 a coaming or breakwater 10 may be secured to the ribs 9 by turn buttons 11, as herein-after described with reference to Fig. 4 of the drawings. In some cases the ribs 9 may 50 be dispensed with, in which case breakwaters may be substituted therefor and be hinged to the upper surface of the member 5 so that they are capable of being swung down sideways when required, so as to expose the face 55 of the pupil or swimmer to free access of water from both sides.

A groove or recess 13 for the chin is provided towards the rear end of the chin supporting member 5 in which may be placed 60 some soft material so as to give comfort to the chin.

The arms 2 have a plurality of holes 14 at their forward ends which are adapted to engage bolts 15 on the underside of the main 65 float and are secured thereto by wing nuts 16,

whereby the effective length and inclination of the arms 2 are varied as required. Each of the arms 2 at its other end is provided with a ring screw 17 which may be attached by a tape or the like to any one of a plurality of rings or eyes 18 secured at convenient points on the outside of the belt, or, instead of the ring screw 17, a snap hook may be fitted to the ends of the arms which are adapted to hook on to the eyes 18. The belt 70 which may be of any suitable material such as canvas or the like is fastened round the abdomen of the swimmer by tapes or straps 75 19 which are attached to the ends of the belt. That portion of the belt which passes round 80 the back of the pupil or swimmer carries the auxiliary float or floats 4, preferably by means of loops 20 formed in or attached to the belt, which loops encompass the float or floats. Tapes may be provided towards 85 either side of the belt and are tied at the back, such tapes passing through holes or loops formed in the belt, whereby the auxiliary floats may be brought closer together or permitted to remain further apart so that 90 the structure will fit pupils or swimmers of varying sizes.

In some cases the auxiliary float or floats 4 may be reduced in size and a depending arm 21 having an adjustable weight 22 95 thereon attached in any suitable manner to the main float 1 as is shown in Fig. 3 of the drawings. When this latter arrangement is employed it is preferable to use auxiliary floats attached to the legs as hereinafter described. The main float 1 may also be provided interiorly with a vertical partition 23 extending longitudinally of the float from a position on the side adjacent the swimmer to within a small distance of a forward position of the side of the float. By this means, when the float has been partially filled with water in order to decrease its buoyancy, such water is caused to remain on either side of the partition and thereby assist in preventing rolling of the main float. The space 24 between the partition and the forward side of the float, and which preferably lies under the neck through which the water is poured, permits of the water reaching 105 both sides of the partition; in an alternative method the partition may extend entirely across the float, in which case holes 110 may be bored in the partition to serve the same purpose as the space 24.

The position of a swimmer when using the appliance is indicated by broken lines in Fig. 1, the main float 1 being partly under his chin, the auxiliary floats 4 at his back, and the diverging arms 2 passing below his armpits so as not to interfere with the free 115 movement of his arms.

The appliance illustrated by Fig. 4 which may be used particularly in imparting instruction in or practicing the breast stroke 120 130

comprises a main float 1 on which are mounted a pair of diverging arms 2 carrying auxiliary floats 4. The floats 1 and 4 may consist of closed metallic or other receptacles normally full of air but provided with necks or equivalents by which they may be partially filled with water in order to vary their buoyancy, or they may be constructed of any material of suitable specific gravity as for instance cork. When this latter arrangement is adopted they are preferably formed in sections or layers as shown in dotted lines in Figs. 4 and 5, the number of which may be increased or decreased in order to vary the buoyancy of the structure.

The float 1 is provided with a groove or recess 13 for the reception of the chin of the swimmer or pupil and the arms 2 which are pivotally connected with ribs or projections 9 on the float 1 have oblique tapered ends 24^g adapted to co-act with oppositely formed ends 25 on raised portions of the ribs 9 and are secured in the position shown by turn-buttons 26. Slidably mounted in grooves 10 in the forward end of the ribs or projections 9 is a screen or partition 12 and detachably secured to the ribs 9 by means of turn-buttons 27 is a celluloid or other transparent coaming 10. The floats 4 are secured to the arms 2 by means of bolts 28 and wing nuts 29, a number of holes 30 being provided in each arm in order that the position of these floats may be adjusted.

An apron 31, a portion or the whole of which may be buoyant, provided with tapes or cords 32, is attached to the float 1 or other suitable part of the device in any suitable manner.

The float 33 illustrated by Fig. 5 is or may be similar to the floats 4, its particular feature being that the loop or equivalent 34 by which it is attached to the legs of the swimmer or pupil is secured to the float 45 proper by a cord or equivalent 35 of sufficient length to permit of the free use of the leg at the proper distance beneath the surface of the water.

The appliance is attached to the pupil or swimmer in the manner illustrated by means of the apron 31 and tapes or cords 32. The floats 33 may or may not be attached to suitable parts of his legs as may be considered desirable.

One method of using the appliance, as illustrated in any of the figures, for the purpose of swimming instruction is as follows: When the pupil enters the water he rests his chin in the groove or recess 13 and proceeds to carry out the strokes in which he has previously been instructed on shore. The screen or coaming 10 prevents water gaining access to his mouth and nostrils and thereby gives him greater confidence in his early efforts. As the pupil progresses in the

art the buoyancy of the floats 1 and 4 may be diminished, if they are in the form of receptacles by inserting a certain amount of water thereinto or if they are in the form of buoyant material by removing one or more sections therefrom. As the pupil still further progresses the coaming 10 may be removed and the screen or door 12 can be raised and eventually removed altogether.

The construction illustrated diagrammatically by Fig. 6 is a modification of that illustrated by Figs. 1, 2 and 4, wherein the main float 1 is of cylindrical formation and slightly larger diameter than the auxiliary floats 4, and has adjustably attached thereto a supporting member 5 to which the arms 2 are secured. The recess 13 for the chin of the swimmer is formed on the upper surface of the member 5, which surface may also carry the breakwater 10 and screen 12 in any suitable manner. A slot 34 extends from the front of the member 5 centrally in a rearward direction for any suitable distance, through which slot a bolt 35 fixed in the main float 1 passes and is secured by a wing nut 36; the member 5 is thus capable of adjustment on the main float 1 for the purpose of varying the point of support for the chin of the swimmer in relation to the centre of buoyancy of the structure, whereby the position of the chin of the swimmer relative to the surface of the water may be varied.

In the modification illustrated in Fig. 7 which is also purely diagrammatic, the structure comprises three similar floats 37 of cylindrical shape connected by the arms 2. A supporting member 38 in which is formed the recess 13 for the reception of the chin of the pupil or swimmer and which may also carry the breakwater and screen, is attached to the arms 2 intermediate their ends, the supporting member being so located as to permit of the recess 13 occupying a position substantially at or in vertical alignment with the centre of buoyancy of the structure. The member 38 may be capable of adjustment on the arms 2. With this construction a result similar to that described with reference to Fig. 5 is obtained whereby the point of support of the pupil or swimmer may be varied in relation to the centre of buoyancy of the structure.

In another form of the invention the buoyant structure may comprise two or more floats, hinged together, one of which may be constructed similarly to the main float 1 and another to afford the necessary support to the pupil's or swimmer's chest and body, while leaving his arms and legs free.

In any construction the floats may be of rubber or the like or a composition thereof and adapted to be inflated or deflated as required.

I claim as my invention:—

1. For use in imparting instruction in or practicing swimming, a buoyant structure comprising a closed hollow body, and a supporting means for the chin of a pupil or swimmer adjustably attached to the upper surface of said hollow body.
2. For use in imparting instruction in or practicing swimming, a buoyant structure comprising a main float member, adjustable supporting means for the chin of a pupil or swimmer attached to the upper surface thereof, two diverging arms adjustably attached to the underside thereof, a belt attached to the body of the swimmer, to which belt the free ends of said diverging arms are attached at any desired point, and two auxiliary hollow bodies fitted to said belt.
3. For use in imparting instruction in or practicing swimming, a buoyant structure comprising a main float member, and a detachable coaming or breakwater provided on the upper surface thereof.
4. For use in imparting instruction in or practicing swimming, a buoyant structure comprising a main float member, and an adjustable coaming or breakwater provided on the upper surface thereof.
5. For use in imparting instruction in or practicing swimming, a buoyant structure comprising a main float member, a supporting means for the chin of a pupil or swimmer provided on its upper surface, and a detachable coaming or breakwater provided on the upper surface of said supporting means.
6. For use in imparting instruction in or practicing swimming, a buoyant structure comprising a main float member, a supporting means for the chin of a pupil or swimmer provided on its upper surface, and an adjustable coaming or breakwater provided
7. For use in imparting instruction in or practicing swimming, a buoyant structure comprising a main float member, a supporting means for the chin of a pupil or swimmer provided on the upper surface thereof, projections on the upper surface of said supporting means and a coaming or breakwater detachably mounted on said projections.
8. For use in imparting instruction in or practicing swimming, a buoyant structure comprising a main float member, a supporting means for the chin of a pupil or swimmer provided on the upper surface thereof, projections on the upper surface of said supporting means, and a screen or partition adjustably fitted intermediate the forward ends of said projections.
9. For use in imparting instruction in or practicing swimming, a buoyant structure comprising a main float member, a supporting means for the chin of a pupil or swimmer adjustably mounted on the upper surface thereof, projections on the upper surface of said supporting means, and a coaming or breakwater detachably mounted on said projections.
10. For use in imparting instruction in or practicing swimming, a buoyant structure comprising a main float member, a supporting means for the chin of a pupil or swimmer adjustably mounted on the upper surface of said supporting means, and a screen or partition adjustably fitted intermediate the forward ends of said projections.

In testimony whereof I have hereunto subscribed my name this fifteenth day of April, 1924.

HAROLD OLSSON.
